HEARING AID MICROPHONE

Harry B. Shapiro, Astoria, Long Island, N. Y., assignor to Sonotone Corporation, Elmsford, N. Y., a corporation of New York

Application August 3, 1940, Serial No. 350,595

7 Claims. (Cl. 179—107)

This invention relates to hearing aid microphones, and particularly to diaphragm-driven hearing aid microphones having vibro-electric transducer elements which are sensitive to variations in humidity, such as Rochelle salt crystal microphones or electret-type condenser microphones.

Among the objects of the invention is a microphone of the foregoing type in which the driving diaphragm forms part of an extremely flat vapor-proof cavity enclosure around its humidity sensitive element, and having acoustic vents which are sealed by a vapor-proof diaphragm barrier so that notwithstanding the vapor-proof seal of the cavity, and the great stiffness of the air sealed therein, the acoustic inertance of the vent resonates with the microphone cavity in the range below about 1000 cycles; a high impedance microphone of the foregoing type which is supported by a yieldable diaphragm behind a sound-pervious casing wall portion, so as to hold the microphone spaced from the casing walls and form an acoustic seal around the space between the sound-pervious casing wall portion and the facing microphone diaphragm; the recessing of the air-pervious microphone casing wall portion relatively to the adjacent casing boundary which is exposed to contact with the user's garment; and the arrangement of the yieldable microphone support relatively to masses associated with the microphone casing so that they prevent and suppress mechanical propagation of noise vibrations from the surface of the microphone casing to the yieldably suspended microphone unit.

The foregoing and other objects of the invention will be best understood from the following description of exemplifications thereof, reference being had to the accompanying drawing wherein

Fig. 1 is a vertical cross-sectional view along line 1—1 of Fig. 2 of a hearing aid microphone exemplifying the invention;

Fig. 2 is a view along line 2—2 of Fig. 1;

Fig. 3 is a vertical sectional view along line 3—3 of Fig. 4 illustrating a wearable electron tube amplifier unit with the microphone of Figs. 1 and 2 mounted therein;

Fig. 4 is a front elevational view of the microphone of Fig. 3 with parts broken away;

Fig. 5 is a view similar to Fig. 1 illustrating a modified arrangement of the microphone; and

Fig. 6 is a front view of the microphone of Fig. 5.

In my copending application Serial No. 294,649,

filed September 13, 1939, is described a novel electron tube amplifier hearing aid which makes it possible to supply the user with the amplified sound required to compensate for his lack of normal hearing acuity, while keeping the electron tube amplifier and the accessories required for its operation extremely light and small so that the complete electron tube hearing aid may be comfortably and inconspicuously worn on the body of the user.

The electron tube amplifier of such hearing aid must be very small and flat so as to fit into a vest pocket of the user and must house not only all the components of the amplifier, but also 15 the microphone for driving the amplifier.

High impedance microphones, such as Rochelle salt crystal or electret-type condenser microphones, have characteristics which make them desirable for use in such electron tube hearing 20 aid amplifiers. However, prior to the invention, the structure of such microphones was very bulky and occupied a disproportionately large part of the small volume available within the compact flat amplifier casing required for housing not only the microphone, but all the elements, including the tubes, of the amplifier unit. Furthermore, when Rochelle salt crystal or electret-type condenser microphones are used as a part 25 of a hearing aid worn on the body of the user, their output is greatly affected by the humidity to which their active elements are exposed. Thus, for instance, the output of a Rochelle salt crystal or an electret microphone drops to almost zero when, under exposure to humidity, its 30 surface leakage reduces its impedance to a fraction 35 of the required operative value.

The requirements with respect to high sensitivity and good frequency response, while protecting the humidity-sensitive transducer structure against variations of humidity in the surrounding air, imposed very strict limitations on the minimum size of such hearing aid microphone, since because of the high sensitivity required from a hearing aid microphone, it must 40 be driven by a relatively large diaphragm exposed to the sound propagated in the surrounding air.

If an attempt is made to house such diaphragm unit in a very flat casing that is sealed against 45 humidity, the stiffness of the air in the small casing cavity greatly reduces its sensitivity in the frequency range below 1000 cycles and makes it practically useless as a hearing aid microphone.

The effect of the stiffness of the air in reducing 50 the sensitivity of such small completely

sealed microphone is overcome by providing the casing wall with an acoustic vent which is sealed with a humidity-proof diaphragm that has such small stiffness and mass compared to the stiffness of the cavity and the acoustic inertance of the vent as to be in its effect similar to an open vent hole.

In Figs. 1 to 4 is shown a hearing aid microphone unit and its mounting in the casing of a wearable hearing aid electron tube amplifier exemplifying one form of the invention. The microphone unit comprises an outwardly tapering conically shaped light vibratory diaphragm 11 having its peripheral edge sealed to the flange 12 of a flat shallow casing wall 13 so as to form a very flat cavity. The diaphragm 11 is very thin so as to reduce its mass, and its outwardly tapered shallow conical shape, in combination with the peripheral corrugation 14, gives it the desired stiffness, while confining its dimensions to a very thin space in its roomiest central part which is just deep enough to house a Rochelle salt crystal transducer unit 16. As an alternative, an electret-type condenser transducer structure may be mounted in the cavity and arranged to be actuated by the diaphragm.

In the form shown, a standard Rochelle salt crystal bimorph 16 of the twister type is used having overall dimensions of $\frac{5}{8} \times \frac{5}{8} \times \frac{1}{32}$ of an inch. Three corners of the crystal unit are secured across spacer pads 17 to the inner face of the casing wall 13, the spacer pads 17 being of a slightly yieldable highly viscous material. To the corner of the crystal 16 which is located underneath the vertex of the conical diaphragm 11 is secured a metallic mounting strip 18 of a driving link 19, the outer end of which is united, as by cementing, to the tip of the diaphragm 11 so that vibrations of the diaphragm are transmitted to the bimorph 16.

One electrode layer of the crystal 16 is connected through a foil strip 21 to a terminal tip 22 which is riveted over an insulating strip 23 to the rear wall 13 of the casing, the insulating strip 24 serving also as an insulating support for another terminal tip 23 to which is connected a similar foil strip 21 extending from the other electrode layer or layers of the crystal. Two insulated cord leads 25 connected to the two terminal tips 22, 23 and tightly sealed by vapor-proof seals in small holes of the cavity wall 13 provide the external microphone output leads. The junction between the diaphragm 11 and the casing 13 and all other junctions and entrances into the microphone cavity are sealed by strong cementitious material which is impervious to water or other vapors and forms a good cementitious junction. Bakelite 6052 cement or Vulcalock give satisfactory results. A microphone cavity sealed against humidity with such cements maintains the sensitivity of the Rochelle salt crystal or electret type transducer unit substantially the same under changes in the humidity of the exterior air up to 100% at which the output of such microphone would fall to substantially zero. In the practical construction, the diaphragm 11 and the flat casing wall are made of aluminum.

In order to reduce the space occupied by the microphone structure to a minimum, the thickness of the flat cavity formed by the microphone structure is reduced to provide just enough space for housing the transducer structure. As a result, the thin layer of air confined in the cavity has high stiffness which cuts down the sensitivity

of the microphone in the range down below about 1000 cycles so that such microphone would be of no practical value for a hearing aid microphone.

In the microphone of the invention, the sensitivity in the low frequency range is raised by forming in the flat casing wall 13 vent holes 31 having an acoustic inertance which, in combination with the stiffness in the air of the microphone cavity, forms a vibrating system which is resonant in the desired part of the low frequency range, for instance, around 400 or 500 cycles, thereby raising the sensitivity of the microphone in the range between 500 and 1000 cycles so that notwithstanding the small thickness of the microphone structure cavity and the great stiffness of the air layer confined therein, it is as effective as any prior bulky hearing aid microphone of a similar type.

The interior of the microphone structure cavity is maintained sealed against humidity notwithstanding the provisions of the vent holes 31, by providing around the portion of the cavity wall 13 in which the vent holes 31 are formed a peripheral ridge 32 to which is united, as by cementing, a sheet element of thin flexible material 33 so as to form a vapor-proof seal thereon.

In the actual construction of such microphone, a thin flexible piece of aluminum foil is used as the sealing layer 33, its stiffness and mass being kept so small compared to the stiffness of the air in the cavity of the microphone structure and the acoustic inertance of the vent holes, as to assure that the vent holes 31 have the full effectiveness that they would have in the absence of the sealing layer 33.

It was found that such sealing layer 33 is effective in sealing the cavity against humidity, while leaving fully effective the action of the vent holes 31, if the resonance of the yieldable layer is made of the order of the resonance of the system formed by the acoustic vents 31 and the stiffness of the air in the cavity. A sealing layer 33 having a resonance at about 400 cycles and vent holes 31 which, in combination with the stiffness of the air in the microphone cavity, form a system resonant at 500 cycles, resulted in a satisfactory, extremely compact hearing aid microphone, with a microphone structure having a thickness of only .165 to .110 inch. The resonance peaks of the vibratory system so formed may be suitably damped, as by cementing over the vent holes 31 a piece of sound-pervious vibration damping fabric 34.

A microphone using a Rochelle salt crystal transducer unit and designed in the way described above has an overall sensitivity and performance of the same character as the best similar diaphragm-driven hearing aid microphones heretofore available, although occupying only a small fraction of the space required by such prior microphones.

A high impedance microphone used as a part of a high gain electron amplifier hearing aid has to operate under conditions utterly different than those encountered in other uses. This is due to the fact that the amplifier casing in which the microphone is usually housed has to be worn more or less hidden under the clothing of the user and connected by a cord to the receiver, resulting in noise vibrations imparted to the cord and to the casing and propagated from the exterior of the casing to the microphone.

According to the invention, the effect of cloth rubbing noises on the microphone output are

practically suppressed by providing the amplifier casing with an acoustically-pervious recessed wall portion behind which the microphone is mounted, so as to form in front of the diaphragm an air space which is acoustically sealed against the back space of the amplifier casing.

In addition, the microphone unit is so mounted behind the sound-pervious wall of the amplifier casing that it is freely supported on a yieldable spacer diaphragm having a great vibration absorbing capacity and impeding propagation of noise vibrations from the casing wall to the microphone.

One form of such arrangement is shown in connection with Figs. 3 and 4 illustrating the flat compact casing small enough for inconspicuous wear in a vest pocket of the user in which is housed an electron tube amplifier and a microphone arranged in the way described in my copending application Serial No. 294,649, filed September 13, 1939, the specification of which is hereby made a part hereof.

As shown in Figs. 3 and 4, the front wall of the amplifier casing 40 is provided with a recessed wall portion 41 which is provided with vent slits 42 so as to render it acoustically pervious. The microphone unit, such as shown in Figs. 1 and 2, is yieldably supported behind the acoustically-pervious recessed wall 41 so that sound is propagated through the vents 42 to the microphone diaphragm.

A diaphragm 43 of yieldable sound absorbing and damping sheet material, such as Neoprene or suitable rubber, has an outer peripheral portion folded and united, as by cementing, over a supporting collar 44 to form in front thereof a sealing bead 45 forming a seal around the sound-pervious casing wall 41 against which it is pressed, and a radially spaced inner portion 46 of the supporting diaphragm 43 is united, as by cementing, to the periphery of the microphone unit so as to hold it floatingly spaced from the casing wall and all other structural elements housed in the casing 40, while forming an acoustic seal around the space between the microphone diaphragm 41 and the recessed wall portion 41.

As explained in my copending application Serial No. 294,649, the electron tube amplifier of the invention utilizes a magnetic core inductance and a magnetic core transformer as a part of the amplifier circuit, the inductance and the core having a substantial mass and being mechanically joined to the casing 40.

By interposing the relatively large mass of the amplifier casing, which is increased by the mass of the magnetic cores of the coupling inductance and the transformer, between the yieldable vibration absorbing diaphragm 43 which holds the microphone unit floatingly spaced from the casing structure, the mechanical propagation of rubbing noises from the exterior of the casing to the microphone unit is very effectively suppressed.

The supporting collar 44 is of a width somewhat larger than the thickness of the microphone so as to protect the microphone unit against contact with the casing and any other elements housed therein, while keeping it yieldably suspended on the yieldable annular diaphragm 43 in the inner space of the ring, and at the same time providing an acoustic seal for the space between the diaphragm and the acoustically-pervious recessed wall 41 of the casing.

The portion of the recessed casing wall 41 facing the supporting collar 44 has an annularly

shaped ridge formation 47 against which the sealing bead 45 is pressed into sealing engagement. As shown in Fig. 3, the supporting collar 44 is held in its proper position by three brackets 48 having legs resting against the elements of the electron tube amplifier assembly mounted within the casing behind the microphone unit.

By recessing the acoustically-pervious wall portion 41 of the casing behind which the microphone is mounted relatively to the other wall surfaces which form the outer boundary of the casing 40, garment parts which come in contact with the outer boundary of the casing are kept away from the edges of the vent openings 42 and generation of noise by rubbing thereon is prevented, and by keeping the microphone yieldably suspended and spaced from the amplifier casing unit, mechanical propagation of noise to the microphone is suppressed.

In Figs. 5 and 6 is shown a modified form of microphone arrangement of the invention. In this arrangement, the delicate diaphragm 41 of the microphone is protected by a dome-shaped circular plate 51 having openings 52 through which sound is propagated to the diaphragm 41 of the microphone. The periphery of the microphone is yieldably supported by the intermediate portion of a collar 53 of yieldable material, such as rubber, having a forwardly extending lip 54 held in engagement with the facing inner border surface of the recessed wall portion 41 of the amplifier casing so as to form an acoustic seal interposed between the space in the back of the microphone and the space between the diaphragm 41 and the recessed acoustically-pervious wall, the rear edge 55 of the yieldable collar engaging and resting on the underlying portions of the electron tube amplifier assembly which occupies the underlying part of the microphone casing.

The rear wall 56 of the extremely thin microphone cavity has a very shallow rearwardly depressed wall portion 57 in which is formed a vent hole 58 which is sealed by a light thin diaphragm 59 cemented to the inner edges of the depressed wall portion, so as to give a vapor-tight humidity seal for the flat microphone cavity, while at the same time keeping effective the vent action of the hole 58, as explained in connection with Figs. 1 and 2.

The principles of the invention explained in connection with specific exemplifications thereof will suggest to those skilled in the art many other applications and modifications of the same. It is accordingly desired that the appended claims be construed broadly, and that they shall not be limited to the specific details shown and described in connection with exemplifications thereof.

I claim:

1. In a microphone unit for a hearing aid that is small enough for inconspicuous wear on the body of the user: a generally flat relatively rigid member forming a cavity wall; a vibratory diaphragm having a periphery joined to said wall to form therewith a shallow vapor-tight cavity enclosure; vibro-electric transducer means including an element enclosed in said cavity and arranged to produce in response to sound acting on said diaphragm a corresponding electric output; said transducer means being of such characteristics that its output is substantially reduced when it is subjected to predetermined variations in the composition of the atmosphere in which it operates; said cavity enclosure having dimensions at which the stiffness of the air confined therein would, in the absence of cavity vents, reduce sub-

stantially the sensitivity of the action of said diaphragm in the frequency range of about 1000 cycles and below; said cavity wall having vent opening portions to the air space on the exterior side of said cavity wall exhibiting an acoustic inertance which resonates with the air of said cavity enclosure at a frequency in the range below 1000 cycles; and a light flexible diaphragm forming a substantially atmosphere-proof seal between the air within said cavity enclosure and said vent opening portions and having its masses and stiffness so arranged and proportioned as to substantially maintain the effectiveness of the acoustic inertance of said vent opening portions with respect to the stiffness of the air confined in said cavity.

2. In a microphone unit for a hearing aid that is small enough for inconspicuous wear on the body of the user: a generally flat relatively rigid member forming a cavity wall; a vibratory diaphragm having a periphery joined to said wall to form therewith a shallow vapor-tight cavity enclosure; vibro-electric transducer means including an element enclosed in said cavity and connected to be driven by said diaphragm so as to produce in response to sound acting on said diaphragm a corresponding electric output; said transducer means being of such characteristics that its output is substantially reduced when it is subjected to predetermined variations in the composition of the atmosphere in which it operates; said cavity enclosure having dimensions at which the stiffness of the air confined therein would, in the absence of cavity vents, reduce substantially the sensitivity of the action of said diaphragm in the frequency range of about 1000 cycles and below; said cavity wall having vent opening portions to the air space on the exterior side of said cavity wall exhibiting an acoustic inertance which resonates with the air of said cavity enclosure at a frequency in the range below 1000 cycles; and a light flexible diaphragm forming a substantially atmosphere-proof seal between the air within said cavity enclosure and said vent opening portions and having its masses and stiffness so arranged and proportioned as to substantially maintain the effectiveness of the acoustic inertance of said vent opening portions with respect to the stiffness of the air confined in said cavity.

3. In a microphone unit for a hearing aid that is small enough for inconspicuous wear on the body of the user: a generally flat relatively rigid member forming a cavity wall; a vibratory diaphragm having a periphery joined to said wall to form therewith a shallow vapor-tight cavity enclosure; transducer means including a vibro-electric transducing element enclosed in said cavity and arranged to produce in response to sound acting on said diaphragm a corresponding electric output; said transducing element being of such characteristics that its efficiency is substantially reduced when it is operated under predetermined excess humidity conditions in the atmosphere; said cavity enclosure having dimensions at which the stiffness of the air confined therein would, in the absence of cavity vents, reduce substantially the sensitivity of the action of said diaphragm in the frequency range of about 1000 cycles and below; said cavity wall having vent opening portions to the air space on the exterior side of said cavity wall exhibiting an acoustic inertance which resonates with the air of said cavity enclosure at a frequency in the range be-

low 1000 cycles; and a light flexible diaphragm forming a substantially vapor-proof seal between the air within said cavity enclosure and said vent opening portions and having its masses and stiffness so arranged and proportioned as to substantially maintain the effectiveness of the acoustic inertance of said vent opening portions with respect to the stiffness of the air confined in said cavity.

4. In a microphone unit for a hearing aid that is small enough for inconspicuous wear on the body of the user: a generally flat relatively rigid member forming a cavity wall; a vibratory diaphragm having a periphery joined to said wall to form therewith a shallow vapor-tight cavity enclosure; transducer means including a vibro-electric transducing element enclosed in said cavity and connected to be driven by said diaphragm so as to produce in response to sound acting on said diaphragm a corresponding electric output; said transducing element being of such characteristics that its efficiency is substantially reduced when it is operated under predetermined excess humidity conditions in the atmosphere; said cavity enclosure having dimensions at which the stiffness of the air confined therein would, in the absence of cavity vents, reduce substantially the sensitivity of the action of said diaphragm in the frequency range of about 1000 cycles and below; said cavity wall having vent opening portions to the air space on the exterior side of said cavity wall exhibiting an acoustic inertance which resonates with the air of said cavity enclosure at a frequency in the range below 1000 cycles; and a light flexible diaphragm forming a substantially vapor-proof seal between the air within said cavity enclosure and said vent opening portions and having its masses and stiffness so arranged and proportioned as to substantially maintain the effectiveness of the acoustic inertance of said vent opening portions with respect to the stiffness of the air confined in said cavity.

5. In a microphone unit for a hearing aid that is small enough for inconspicuous wear on the body of the user: a generally flat relatively rigid member forming a cavity wall; a vibratory diaphragm having a periphery joined to said wall to form therewith a shallow vapor-tight cavity enclosure; transducer means including a vibro-electric transducing element enclosed in said cavity and connected to be driven by said diaphragm so as to produce in response to sound acting on said diaphragm a corresponding electric output; said transducing element being of such characteristics that its efficiency is substantially reduced when it is operated under predetermined excess humidity conditions in the atmosphere; said cavity enclosure having dimensions at which the stiffness of the air confined therein would, in the absence of cavity vents, reduce substantially the sensitivity of the action of said diaphragm in a part of the frequency range of about 1000 cycles and below; said cavity wall having vent opening portions to the air space on the exterior side of said cavity wall exhibiting an acoustic inertance which resonates with the air of said cavity enclosure at a frequency in the range below 800 cycles; and a light flexible diaphragm forming a substantially vapor-proof seal between the air within said cavity enclosure and said vent opening portions and having its masses and stiffness so arranged and proportioned as to substantially maintain the effectiveness of the acoustic inertance of said

vent opening portions with respect to the stiffness of the air confined in said cavity.

6. In a wearable electron-tube amplifier hearing aid, a flat amplifier casing small enough for substantially hidden wear on the body of the user and having two walls enclosing the opposite sides of a relatively shallow interior space; one of said walls having a sound pervious wall portion; a microphone unit located in said interior casing space for cooperation with the amplifier elements of said hearing aid; said microphone comprising a vibratory diaphragm located adjacent said sound pervious wall portion so as to be actuated by sound propagated therethrough; a generally flat relatively rigid microphone cavity wall member having a periphery joined to said diaphragm to form therewith a shallow vapor-tight microphone cavity enclosure of a thickness of the order of one-half the thickness of said casing or less; transducer means including a vibro-electric transducing element enclosed in said cavity and arranged to produce in response to sound acting on said diaphragm a corresponding electric output; said transducing element being of such characteristics that its efficiency is substantially reduced when it is operated under predetermined excess humidity conditions in the atmosphere; said microphone cavity enclosure having dimensions at which the stiffness of the air confined therein would, in the absence of cavity vents, reduce substantially the sensitivity of the action of said diaphragm in a part of the frequency range of about 1000 cycles and below; said cavity wall having vent opening portions to the air space within said casing on the exterior side of said cavity wall and being arranged so that said vent opening portions exhibit an acoustic inertance which resonates with the air of said cavity at a frequency in the range below 1000 cycles; and a light flexible diaphragm forming a substantially vapor-proof seal between the air within said cavity and said vent opening portions and having its masses and stiffness so arranged and proportioned as to substantially maintain the effectiveness of the acoustic inertance of said vent opening portions with respect to the stiffness of the air confined in said cavity.

7. In a wearable electron-tube amplifier hearing aid, a flat amplifier casing small enough for substantially hidden wear on the body of the user and having two walls enclosing the opposite sides of a relatively shallow interior space; one of said walls having a sound pervious wall portion; a microphone unit located in said interior casing space for cooperation with the amplifier elements of said hearing aid; said microphone comprising a vibratory diaphragm located adjacent said sound pervious wall portion so as to be actuated by sound propagated therethrough; a generally flat relatively rigid microphone cavity wall member having a periphery joined to said diaphragm to form therewith a shallow vapor-tight microphone cavity enclosure of a thickness of the order of one-half the thickness of said casing or less; transducer means including a vibro-electric transducing element enclosed in said cavity and connected to be driven by said diaphragm so as to produce in response to sound acting on said diaphragm a corresponding electric output; said transducing element being of such characteristics that its efficiency is substantially reduced when it is operated under predetermined excess humidity conditions in the atmosphere; said microphone cavity enclosure having dimensions at which the stiffness of the air confined therein would, in the absence of cavity vents, reduce substantially the sensitivity of the action of said diaphragm in a part of the frequency range of about 1000 cycles and below; said cavity wall having vent opening portions to the air space within said casing on the exterior side of said cavity wall and being arranged so that said vent opening portions exhibit an acoustic inertance which resonates with the air of said cavity at a frequency in the range below 1000 cycles; and a light flexible diaphragm forming a substantially vapor-proof seal between the air within said cavity and said vent opening portions and having its masses and stiffness so arranged and proportioned as to substantially maintain the effectiveness of the acoustic inertance of said vent opening portions with respect to the stiffness of the air confined in said cavity.
